UNITED STATES PATENT OFFICE.

CLARENCE A. ANDERSON, OF ABILENE, KANSAS.

ELECTRICAL TESTING SYSTEM AND APPARATUS.

1,384,734.

Specification of Letters Patent. Patented July 19, 1921.

Application filed September 24, 1919. Serial No. 326,005.

To all whom it may concern:

Be it known that I, CLARENCE A. ANDERSON, a citizen of the United States, residing at Abilene, in the county of Dickinson and State of Kansas, have invented certain new and useful Improvements in Electrical Testing Systems and Apparatus, of which the following is a specification, reference being had therein to the accompanying drawing.

10 My invention relates to testing sets and more particularly to an arrangement and combination of circuits and apparatus for use as a troubleman's or lineman's portable test set.

15 An object of the invention is to provide a simple and effective means for the location of various faults or defects in circuits such as telephone and telegraph line circuits.

Another object of the invention is to provide a convenient and effective arrangement for making certain tests without the necessity of disconnecting or otherwise disarranging the circuits being tested and without having to break through the insulation.

25 A further object of the invention is to provide a novel form of finder or exploring coil arranged to be conveniently held in operative relation with the conductor being tested.

30 Various other objects of my invention will be apparent from a perusal of the accompanying specification and drawing.

My invention is illustrated in the accompanying drawings, in which:

35 Figure 1 is a diagram of the circuit arrangement;

Fig. 2 is a side view of the exploring coil;

Fig. 3 is an end view thereof showing the 40 movable clamping side open; and

Fig. 4 is a view showing the holder for the exploring coil and its cable attached to the wall of a suitable instrument box.

Referring to the drawings in particular, 45 and first to the diagram of Fig. 1, 1 indicates a telephone magneto generator of the standard or well known type having contacts such as 2, 3, 4 and 5 arranged to be automatically operated upon operation of the

50 generator in a manner well known to those skilled in the art, in the present case the arrangement being such that upon operation of the generator the contact 2 will move outwardly into engagement with contact 3, 55 moving the contact 3 out of engagement.

with contact 4 and into engagement with contact 5, so that contacts 2, 3, and 5 remain in electrical connection during operation of the generator. In addition to these usual automatically operated contacts, I provide 60 an additional make and break switch element 6 operated in the operation of the generator. This switch consists of a movable contact element 7 mounted to turn in fixed relation with the shaft 8 of the magneto 65 armature and arranged to make contact with a brush or contact spring 9 twice during each revolution of the shaft. The contact element 7 is insulated from the shaft 8 or framework of the magneto as indicated dia- 70 grammatically at 10, but is electrically connected with the free or ungrounded terminal of the magneto winding 11. Continuous electrical connection is established between the free end of the armature winding and the fixed terminal 12 through the brush or contact member 13. The contact member 7 is so set or timed in relation to the cycle of the generator that it will make contact with the spring 9 immediately after the 75 peak of the current wave of the generator is reached, which occurs twice for every revolution of the armature. Connection is ex- 80 tended from the free side of generator at 12 through conductor 14, to the line terminal 85 post 15 of the test set. The set is provided with a telephone receiver 16, transmitter 17, induction coil 18, battery 19 and condenser 20, the secondary winding 21 of the induction coil and the receiver 16 being normally 90 connected in series across the line terminal posts 15 and 22, through the normally closed contacts 3-4, 23-24, and 25-26, by way of conductors 27, 28, 29, 30, 31 and 32. The primary winding 34 of the induction coil, 95 the transmitter 17 and battery 19 are connected in series through a suitable normally open controlling key or push button 33. A resistance 35 suitably proportioned to the re- 100 sistance of the receiver, is connected in the shunt of the receiver terminals through the normally closed contacts 23-24 and the normally open generator-controlled contacts 3-5.

It will be noted that the normally closed 105 contacts 25-26 which connect one terminal of the receiver to the line post 22 also normally maintain a short-circuit across the terminals of the condenser 20. The normally closed contacts 25-26 and 23-24, and nor- 110

- mally open contacts 26—36 and 24—37 constitute the contacts of a single key or push button 38 which may be of any known type capable of controlling the connections in a 5 manner similar to that shown. The contacts 26—36, when closed, connect the condenser 20 across the line terminal posts 15 and 22 through the intermittent contact spring 9 by way of conductors 39 and 14. 10 The contact 36 is also connected through conductor 40 to one terminal of a finder or exploring coil 41, the other terminal of which is connected through conductor 42 to contact 37 so that actuation of the key 38 to 15 close contacts 26—36 and 24—37 connects the exploring coil in series with the receiver via conductors 30 and 31. The conductors 40—42 are preferably in the form of flexible leads of suitable length to enable the exploring 20 coil to be moved about for the purpose of placing it in inductive relation to a circuit being tested, for example the line circuit indicated by the dotted lines 43—44. Connection is extended from the line terminal 25 posts 15—22 to the circuit to be tested, for example the line 43—44, in any suitable manner as through a pair of flexible conductors 45—46 terminating in test clips 47—48, respectively. 30 The entire apparatus with its various circuit connections may be mounted in any suitable manner for convenience in use and portage as is usual with linemen's test sets of the portable type, as by mounting in a 35 box or casing with the receiver leads, conductors 40—42 and 45—46 in the form of flexible leads or cords in order that the receiver may be conveniently held to the ear or carried on the head in the form of a head 40 set and the exploring coil and test clips manipulated as the situation demands. 45 In whatever manner the apparatus may be mounted, for convenience in use, I prefer to make the exploring coil in the form substantially as shown in Figs. 2 and 3 and to use an arrangement for carrying it and its flexible connection or cord on the casing or whatever form of mounting is provided for the apparatus. 50 This exploring coil consists of an oblong electromagnet or coil 50 having a core 51 and upper and lower iron pole pieces or pole faces 52 and 53 extending the length of the oblong coil as shown in dotted lines in Fig. 55 2. The windings of the electromagnet 50 are covered or incased on the outside with a suitable protective covering, preferably thin leather or kid, to prevent chafing of the insulation of the outer layer, such covering 60 being suitably water-proofed as with shellac or varnish. The magnet spool with its iron pole faces 52—53 is clamped to a metallic holder 54 of L-shaped cross-section extending the length of the magnet, by means of 65 suitable bolts 55 which extend through the magnet core and are clamped by means of the nuts 56 at the bottom of the coil. These bolts and nuts serve also to hold in place a strip of insulating material 57 and the connecting terminals 58 and 59, which connecting terminals are electrically insulated from the nuts and bolts in a well known manner, not shown. The terminals of the magnet are connected with the connecting terminals as indicated in dotted lines at 60 and 61, 70 while the leads 45 and 46 are connected to the connecting terminals by means of binding screws 62 and 63, respectively. The coil, as a whole, is carried on one of the jaws 64 of a spring clip 65, being held thereon by 75 means of bolts or screws 66. The other jaw 67 of the spring clip engages the side of the magnet, the adjacent side of the magnet being provided with a longitudinal groove 69 to receive and hold a wire or conductor 80 between the magnet and the jaw 67. The spring clip 65 here shown is of a standard type in which the jaws are held together under tension of a clamping spring 70 in the form of a split cylinder, portions of the jaws 85 being extended down to form handles 71 and 72 by which the jaws may be opened against the tension of spring 70. In use the coil is clamped on the wire being tested by operating the handles 71—72 to open the jaws of 90 the clip, inserting the wire between the insulated jaw and the coil with the wire resting in the groove 69 and then releasing the handles to permit the jaw 67 to hold the wire up against the side of the magnet in the groove 100 so that it will lie parallel to the windings of the coil. The spring clip here shown is of a well known form of paper clip or binder, an important requirement being that it be made of iron, whereby when the jaw 76 is 105 closed against the coil 50 with the wire to be tested clamped therebetween the coil and the portion of the wire so clamped will be surrounded by a wall of magnetic material consisting of the top and bottom iron pole 110 pieces or pole shoes 52 and 53 and the iron jaws 64 and 76 of the spring clip, thus acting to form a closed magnetic circuit for the coil and prevent outside circuits from having any inductive effect on the coil winding. 115 Referring now to Fig. 4, 77 indicates a portion of the side wall of a box or other mounting for the apparatus of the test set to which is secured the coil and cable holder 78 comprising an oblong head piece 79 spaced from the mounting member 77 by a pair of posts such as 80 near each end of the oblong head member, the parts being held in the relation shown by means of suitable screws or bolts 81 passing through the 120 head and the centers of the posts into the mounting member 77. The coil and cable are carried by the holder in the manner shown in Fig. 4. The cable comprising the 125 twisted pair of conductors 44—45, when not 130

in use, is held in place by coiling it around the posts 80 between the mounting member and the head 79 as shown in the drawing, the coil being held by passing the handles 5 71 and 72 down over the twisted pair 44-45 and the head 79 as shown in the drawing, one handle being wedged between the coil formed by the twisted pair and the mounting member 77 and the other handle resting 10 against the outer face of the head 79, the parts being so arranged that the handles will be so held with sufficient friction to hold the coil 50 in place and at the same time prevent the coil formed by the twisted 15 pair 44-45 from becoming accidentally dislodged from the holder.

The exploring coil and the manner of holding the same with its flexible leads on the mounting member, is new and I shall 20 therefore claim the same as part of my invention.

In using the device, the lineman places the receiver on his head, the receiver being preferably provided with the usual form of 25 head clamp for this purpose, and if testing for a ground on a metallic circuit, one of the test clips, for example 48, is connected to a ground wire or other good ground connection and the other clip 47 connected first 30 to one line and then the other. With each of the two latter connections, the lineman operates the generator, whereupon a grounded or closed circuit will be indicated by part of the generator current flowing through the 35 receiver, the path of which may be traced as follows: From armature winding 11 of the generator, brush 13, conductor 14, test clip 47, over the line being tested through ground to test clip 48, conductor 32, normally closed 40 contacts 25-26, conductor 31, receiver 16, conductor 30, normally closed contacts 23-24, conductor 29, contacts 3-2 to generator, part of the current being shunted through the resistance 35 by way of contacts 5-3-2. The presence of a ground being thus detected, the exploring coil is 45 clamped on the wire in trouble and the generator again operated with the push button 38 closed which closes the normally open 50 contacts 26-36 and 24-37. If no tone is noticed in the receiver, the exploring coil is removed and clamped to the same wire but to the other side of the test clip 47 and if a tone is then heard in the receiver it indicates 55 that the ground is on that side of the test clip. Thus, if the tone is heard when the coil is clamped to one side of the clip and not on the other, the direction of the trouble is toward the finder coil where the 60 tone is heard. This tone is produced by a current induced in the finder coil which traverses the following path: From finder coil 41 over conductor 40, contacts 26-36, conductor 31, receiver 16, conductor 30, 65 contacts 24-37 and conductor 42 back to

the finder coil, the circuit of the shunt coil 35 now being open at contacts 23-24. The current in the finder coil 41 is induced from an alternating current passing through the line wire to which the coil is clamped, for 70 example 43 indicated in dotted lines. This is a special form of test current produced in the operation of the generator and having certain advantageous qualities resulting from the novel combination and arrangement of circuits and apparatus here disclosed. 75

The circuit of the test current may be traced from generator winding 11, brush 13, conductor 14, test clip 47, line conductor 43, 80 ground fault G, through ground to test clip 48, condenser 20, conductor 21, resistance 35, contacts 5-3-2, and back to generator, the winding of the generator being shunted at each half revolution of the armature by way 85 of intermittent contacts 7-9, conductor 39, contacts 26-36, conductor 31, resistance 35, contacts 5-3-2 to generator frame.

As before stated, this closure of the intermittent contacts 7-9 and consequently the 90 shunting out of the generator occurs a moment after the peak of the output curve of the generator is reached. This shunting out of the generator reduces the resistance of the test circuit by removing the 95 generator therefrom and at the same time permitting the condenser to discharge back over the circuit being tested, the discharge circuit being traced from condenser 20, over conductor 46, test clip 48, through ground 100 to ground fault G, thence over conductor 43, test clip 47, conductor 14, brush contact 13, intermittent contacts 7-9, conductor 39, contacts 26-36, and back to condenser 20. It will be seen that this shunting of the generator 105 and discharge of the condenser will effect an instantaneous alternation of the current thus producing a sharp peak in the current curve which makes for maximum efficiency in the inductance effect of the test current on the exploring coil. It will be seen from the above that two impulses will be produced for each half revolution of the generator armature. 110

The lineman perceiving the tone in the receiver continues to move the exploring coil and test clip 47 along the wire at increasing distances from the point where the test clip 47 was first placed in a direction toward the point where the ground fault was found to 120 exist. This exploration continues until no tone is audible in the receiver when the generator is operated, which indicates that the exploring coil is at or past the location of the ground fault, assuming of course that 125 the circuit beyond is open and that the ground fault is the only one.

The lineman may locate the point where two line conductors are crossed with the method above described for locating the 130

ground fault, except that the test clips 47-48 are connected one to each of the lines and the exploring coil placed on one of the lines, and the exploration continued until the 5 place where the lines are crossed is reached.

In testing for shorts, the method is the same, except that the lineman knows without testing which lines are crossed or short-circuited and simply proceeds to trace the 10 path of the test circuit with the finder coil to the point where the fault exists.

The lineman will be able to tell whether the line is open without resorting to the use of the exploring coil, by simply placing 15 the receiver to his ear and operating the generator. No sound will be heard in the receiver if the line is open, while if it is closed, a portion of the generator current will flow through the receiver giving the 20 indication of the closed circuit. From experience the lineman will be able to judge with fair accuracy the distance to the trouble by the volume of sound produced in the receiver. This is especially true in locating 25 trouble on copper toll lines. For example, if the defect is so far away that the lineman can hardly perceive the tone in receiver, the distance is the equivalent of fifty miles of No. 10 B & S copper metallic circuit. As 30 he gets closer to the trouble the tone gets louder and as he gets beyond it such will be indicated by a low tone.

To talk with the set, the clips are connected across the line conductors or in the 35 line circuit and the push button 33 closed, the closure of the button 33 completing the battery supply circuit for the transmitter and the primary winding of the induction coil.

40 By using a high resistance receiver and exploring coil for testing, the same receiver may be used for talking which enables the use of the set to be quickly changed from that of a testing set to a portable telephone set by simply operating the keys or buttons 45 38 or 33.

45 In the location of swinging shorts the high potential caused by the discharge of the condenser brings the swinging short-circuiting connection into circuit, even though the contact may be a poor one and of high resistance, so that it can be located.

50 While I have herein described and illustrated a specific embodiment of my invention, it is to be understood that I do not limit myself to such specific form, but contemplate all such modifications and variants thereof as fairly fall within the scope of the appended claims.

55 Having thus described my invention what I claim and desire to secure by Letters Patent is:—

60 1. In an electrical testing system, a condenser and a magneto generator arranged to 65 be connected in series with a circuit to be

tested, means operated in unison with the generator to shunt the generator out of circuit near a period of high power output of the generator, and means for detecting the presence of the current so produced in the 70 circuit.

2. An electrical testing system as defined in claim 1 in which the generator is intermittently shunted out of circuit while maintaining the condenser in series with the said 75 circuit to prevent the flow of direct current through said circuit.

3. In an electrical testing system, a condenser and a magneto generator arranged to be connected in series with a circuit to be 80 tested, and circuit controlling means operable in unison with the generator to cause said condenser to be charged and discharged in series with the said circuit and to shunt said generator out of circuit during discharge of the condenser.

4. An induction exploring coil having an iron core and winding therefor, magnetic iron pole pieces for said core, a return yoke of iron connecting said pole pieces across one 90 side of said coil and forming a magnetic yoke or return connection and a second magnetic yoke of iron situated on the other side of the coil and arranged to be moved to and from the coil to clamp and hold a conductor between it and the coil, whereby when a conductor is clamped between the movable yoke and the coil the movable yoke completes a screen of magnetic material encircling said conductor and coil to prevent inductive influence on the coil or conductor from external sources.

5. In an electrical testing set, instrument mounting means, a telephone receiver having flexible leads secured at one end to the 105 mounting means, an exploring coil having flexible leads secured at one end to the mounting means, a stationary reel carried by said mounting means arranged to receive the flexible leads of the exploring coil coiled 110 thereon, a head member on said reel arranged to hold the coil in place, a casing of magnetic material surrounding the sides and polar ends of said exploring coil, having one side movable to admit a conductor within 115 the casing between the coil and the movable side, spring clamping means tending to hold said casing closed, and a pair of levers or handles connected one with the casing and the other with the movable side for opening 120 and closing said casing against the tension of said spring clamping means, said handles projecting from said coil and being arranged to straddle said flexible lead coil and said reel head and to be held in clamped engagement therewith on the mounting means.

6. In an electrical testing system, a talking set including an induction coil, receiver, transmitter and battery, an exploring coil and switching means for alternately connect- 130

ing and disconnecting said receiver with the remainder of said talking set and said exploring coil.

7. An electrical testing system as claimed in claim 6 having a telephone magneto generator and a pair of testing leads connected in series with the receiver and means for shunting the receiver through a predetermined resistance during operation of the generator.

8. An electrical testing system as claimed in claim 7 including a condenser and in which the switching means is operable to connect the condenser in series with the generator upon connection of the receiver with the exploring coil and to short-circuit the terminals of the condenser when the re-

ceiver is connected with the armature of the talking set.

9. In an electrical testing system, a talking set including a transmitter, a circuit therefor and a receiver and receiver circuit inductively connected with said transmitter circuit, a magneto generator and means operable upon operation of the generator to disconnect the receiver circuit from inductive relation with the transmitter circuit and connect the generator circuit with the receiver circuit.

In testimony whereof I affix my signature. 30
